UNITED STATES PATENT OFFICE

CHARLES A. FINLEY, OF RUTHERFORD, NEW JERSEY, ASSIGNOR TO BOORUM & PEASE COMPANY, OF BROOKLYN, NEW YORK, A CORPORATION OF NEW YORK

VISIBLE-LOOSE-LEAF DEVICE

Application filed July 11, 1928. Serial No. 291,991.

This invention relates to a follower for use in a visible card index panel or drawer wherein sheets or cards are slidably mounted, the purpose of the follower being to abut against the end of the series of cards or sheets to assemble them and keep them spaced from one end of the panel or drawer, and to hold them in the desired overlapped relation to each other.

10 The follower of this invention is adapted for use with any kind of card or sheet in such a panel or drawer and is particularly useful with cards or card holders having a main portion hinged to a supporting portion.

15 Followers which have been used heretofore have either been clumsy and complicated, or else they have had a tendency to ride under or over the card against which they were intended to abut. In hinged cards having a

20 main portion and a supporting portion the follower is ordinarily intended to abut against the supporting portion at the hinge; but as it rides under the main portion, it is automatically guided under the supporting portion as well, unless prevented.

25 The object of this invention is to provide a follower of simple construction which will efficiently engage the card, and will be prevented from riding over or under the portion of the card against which it is intended to abut.

Other objects will appear from the following specification and claims.

In the drawings:

30 Figure 1 is a plan view of part of a panel showing a part of my follower, and the supporting portions, but no main portion, of several hinged cards;

Figure 2 is a similar plan view but showing 40 the hinged cards with main portions partially broken away.

Figure 3 is a vertical cross-section through one side of the panel taken on the line 3—3 of Fig. 1.

45 Figure 4 is a vertical cross-section on the line 4—4 of Figure 1.

Figure 5 is a vertical cross-section on the line 5—5 of Figure 2.

50 Figure 6 shows a spring-pressed form of follower; while

Figure 7 is a longitudinal section taken on a line corresponding to 7—7 of Fig. 6, showing the follower of Figure 6 inserted in a panel.

In the drawings follower 20 is shown abutting hinged cards 10 in the panel 11. The panel is provided with opposed inwardly facing flanges 12 which overlie the ends 14 of the supporting portions 13 of the cards. The main portion 10 of each card is hinged at 15 to the supporting portion.

The top of the follower abuts against the card in the panel at the hinge line 15.

By card I refer to any form of filing card or sheet or card holder. Hereinafter when I use the term supporting portion I refer to that part which engages the flanges, while by main portion I refer to the portion attached or hinged to the supporting portion. The two portions may or may not be integral. The main portion may be itself the information-bearing element, or it may be any of the many forms of devices or parts by which an information-bearing element is carried. By panel I refer to a panel, drawer or equivalent filing means for assembling cards or card holders.

The follower 20 may be made of cardboard, sheet metal or any suitable material.

It is composed of a body portion 21 having transverse to and intersecting the edge which abuts against the cards, one or more novel crimps or channels 22, and having lugs at each side edge to straddle the flanges 12 of the panel.

In the drawings it is the top edge 27 of the follower which abuts against the cards and the crimps intersecting that edge are formed by the two channels 22 recessed below the surface, or rearward of the plane of the remainder of the body of the follower and extending perpendicularly from top edge 27 to bottom edge 28. The length of the crimps is optional; they need not extend to the opposite edge of the card. The angle of the crimps to the abutting edge of the follower is also optional. In the accompanying drawings the channels are shown located near the side edges of the follower, adjacent the inner ends of the slits 25 which separate the lugs 23 and 24.

from the lug 26, but the location of these crimps or channels on the body of the follower is optional, provided only that they intersect the abutting edge of the follower.

5 The follower is shown in the drawings with three lugs 23, 24 and 26 on each side separated by the slits 25. The central lug 26 underlies the flange and the outer lugs 23 and 24 overlie the flange.

10 In the form illustrated, the central lug is in the plane of the bottom or lowest part of the crimp, while the two outer lugs are in the plane of the remainder of the body portion of the follower.

15 If overlapping hinged cards such as those shown in the drawings are to be supported in a panel, the follower will slide under the main portion 10 of the cards, as illustrated in Fig. 2, but will abut against the supporting portion 13 of the cards at the hinge line 15.

20 By pushing up with the follower against the supporting portions of the cards the cards will be compactly assembled together, and held spaced as desired between the top and bottom of the panel, and in the desired overlapping relation to each other.

25 Due to the construction of my follower, it will not ride over or under the edge of the card, or of the supporting portion of the card, against which it is supposed to abut. The crimp or channel in the abutting edge of the follower prevents this by the fact that the lowest point of the crimp hugs the floor 16 of the panel, while the remainder of the body of the follower is spaced by the crimp higher than the supporting portion of the card can rise when its ends are retained in the flanges of the panel. Thus the top of the follower will abut against the lower edge of the supporting portion of the card, as shown in Figs. 3 and 4.

30 In those figures the card is shown flexed on the hinge, with the main portion standing up approximately at right-angles to the supporting portion and to the panel.

35 My follower is easily adjusted in a panel. Grasping it by the top edge 27 and bottom edge 28, the underlying lug 26 on one side edge may be inserted under the flange 12 on that side, then flexing the follower slightly, the underlying lug on the opposite side edge may be inserted under its flange, and the follower may be slid up the panel to the desired location.

40 The follower will remain at any desired location between the top and bottom of the panel, and it will not become displaced unless pressure is applied to it, to intentionally slide it up or down upon the panel.

45 I sometimes find it convenient to provide a spring 17 having fingers 18, which exert pressure upon the overlying side lugs 23 and 24. This spring assists in maintaining a grip of the straddled lugs of the follower upon the flange of the panel. It is particularly useful

50 in followers in which the distance between the inner ends of slits 25 is less than the distance between the free edges of the flanges 12. It also serves as a protection to the overlying lugs as it causes them to lie flatly against the flange and lessens the danger of their being damaged and accidentally torn off in the handling of the panel.

55 If desired, holes 19 in the body of the follower may be provided into which the finger tips may be inserted to facilitate sliding the follower up and down the panel.

I claim:

1. In a loose leaf filing device a follower having an abutting edge intersected by a crimp.

2. In a loose leaf filing device, a follower having a crimp intersecting the abutting edge, and having lugs on each side edge.

3. In a loose leaf filing device, a follower having a crimp intersecting the abutting edge, the remainder of the body of the follower being spaced above the bottom of the crimp.

4. In a loose leaf filing device, a follower having adjacent each side edge a channel intersecting the top edge and perpendicular thereto, and having lugs on each side edge.

5. In a loose leaf filing device, a follower having adjacent each side edge a channel intersecting the top edge and perpendicular thereto, and forming a recess lying rearward of the plane of the remainder of the body of the follower, in combination with lugs on each side edge.

6. In a loose leaf filing device, a follower having a top edge intersected by a crimp, and having lugs on each side edge adapted to overlie and underlie flanges of a panel, in combination with a spring on said follower exerting downward pressure upon the overlying lugs.

7. In a loose leaf filing device, a panel having opposed flanges and cards slidably mounted thereon in combination with a follower having a crimp intersecting the abutting edge, and having a plurality of lugs on each side edge straddling the flanges.

8. In a loose leaf filing device, a panel having opposed flanges and cards slidably mounted thereon in overlapping relation in combination with a follower adapted to abut against a card and having a crimp intersecting the abutting edge, and having lugs on each side edge straddling the flanges, the bottom of the crimp hugging the floor of the panel.

9. In a loose leaf filing device, a panel having inwardly facing opposed flanges and cards slidably mounted thereon in overlapping relation in combination with a follower slidably mounted on the panel, the follower having adjacent each side edge a channel intersecting and perpendicular to the edge of the follower which abuts a portion of one of

the cards and having on each side edge a lug underlying and a lug overlying the corresponding flange of the panel, the bottom of the channels hugging the floor of the panel and the remainder of the body of the follower being in a plane spaced above the floor of the panel and above the portion of the card against which the follower abuts.

10. In a loose leaf filing device, a panel having opposed flanges and cards each comprising a main portion hinged to a supporting portion the latter being slidably mounted on the panel, in combination with a follower slidably mounted on the panel, the edge of the follower abutting the supporting portion of the cards being intersected by a crimp.

11. In a loose leaf filing device, a panel having opposed flanges and cards each comprising a main portion hinged to a supporting portion the latter being slidably mounted on the panel, in combination with a follower slidably mounted on the panel, the edge of the follower abutting the supporting portion of the cards being intersected by a crimp, no portion of the follower being lower than the bottom of said crimp.

In testimony whereof I have signed my name to this specification.

CHARLES A. FINLEY.
